UNITED STATES PATENT OFFICE.

CLEARMONT V. BEST, OF CANTON, OHIO.

DESIGN FOR A GAS-VAPORIZING FRAME.

SPECIFICATION forming part of Design No. 34,676, dated June 18, 1901.

Application filed May 6, 1901. Serial No. 59,062. Term of patent 8½ years.

To all whom it may concern:

Be it known that I, CLEARMONT V. BEST, a citizen of the United States, residing at Canton, in the county of Stark and State of Ohio, have invented and produced a new and original Design for Gas-Vaporizing Frames, of which the following is a specification, reference being had to the accompanying drawings, forming part thereof.

Figure 1 is a side elevation. Fig. 2 is a top view.

As shown in the drawings, the leading or material feature of my design consists of a circular plate 1, provided with a series of radial openings or apertures 2, located a short distance from the periphery of the circular plate 1, and it further consists in laterally-extending arms 3 and 4, extending diametrically opposite from the circular plate 1. The arm 3 is provided with the enlarged portion 5, which enlarged portion is provided at its end with the annular bead 6. The extension 4 is provided with the plain straight top 7 and the in-

clined bottom 8. The extension 4 is extended a short distance under the plate 1 and is terminated at the point 9, from which point extends the circular bar 10, which circular bar is located at an angle to the plate 1 and its lowest end provided with the enlarged head 11.

Between the laterally-extending arms 3 and 4 and under the plate 1 is located the flange 12, which flange is tapered between the points 13 and 14.

Having fully described my invention, what I claim as new, and desire to secure by Letters Patent, is—

The design for a gas-vaporizing frame, as herein shown and described.

In testimony that I claim the above I have hereunto subscribed my name in the presence of two witnesses.

CLEARMONT V. BEST.
